UNITED STATES PATENT OFFICE.

SAMUEL FURMIDGE, OF CHICAGO, ILLINOIS.

RECOIL CHECK.

Application filed August 13, 1919, Serial No. 317,298. Renewed June 26, 1922. Serial No. 570,938.

To all whom it may concern:

Be it known that I, SAMUEL FURMIDGE, a citizen of the United States, residing at Chicago, county of Cook, State of Illinois, have 5 invented a certain new and useful Improvement in Recoil Checks, and declare the following to be a full, clear, and exact description of the same, such as will enable others skilled in the art to which it pertains to 10 make and use the same, reference being had to the accompanying drawings, which form a part of this specification.

My invention has for its object to produce a simple, compact, efficient and durable device adapted to be connected between two members, one of which is supported from the other by means of springs, and reduce the recoil of the springs after they have been compressed.

20 A further object of the present invention is to produce a simple and novel recoil check in which the resistance will be substantially uniform throughout the entire range of movements of the co-operating parts.

25 The various features of novelty whereby my invention is characterized will hereinafter be pointed out with particularity in the claims; but for a full understanding of my invention, and of its objects and advantages, reference may be had to the following 30 detailed description taken in connection with the accompanying drawings, wherein:

Figure 1 is a side view of a device arranged in accordance with a preferred form 35 of my invention, the housing being shown in section;

Fig. 2 is a section taken approximately on line 2—2 of Fig. 1;

Fig. 3 is a view similar to Fig. 2, the holding plate illustrated in Fig. 2 being omitted; and

Fig. 4 is a section taken approximately on line 4—4 of Fig. 1.

Referring to the drawing, 1 represents a 45 suitable drum adapted to be attached, for example, to the frame of an automobile; the drum being disposed on one side of a circular plate, 2, on the opposite side of which is a suitable clamping jaw, 3, for holding the 50 device in place. Surrounding the drum is an almost complete ring, 4, having a width approximately equal to the axial length of the drum. The ring is preferably faced on the inner side with a layer, 5, of material 55 such as used for brake bands, so as to create considerable frictional resistance when it is

attempted to slide the ring around the drum while pressure is exerted tending to hold the ring against the drum. Beside the end of the drum lies a strong spiral spring, 6, 60 the outer end of which is connected to the drum as indicated at 7, while the inner end is bent radially into the form of an arm, 8, and is connected in any suitable way to one end of the ring as indicated at 9. A cable, 10, is wrapped around the drum over the ring, one end of the cable being attached to one end of the ring and the other end being continued beyond the device for attachment to the axle of an automobile. The cable is 65 preferably attached to the same end of the ring as that to which the spring is connected. This may conveniently be accomplished by employing an eye-bolt, 11, between the ring and the spring, the bolt being made long 70 75 enough to permit the cable to be tied upon or looped about one end, as indicated at 12.

The spring surrounds a short hub, 13, projecting axially from the drum, and revoluble on this hub is a guard plate, 14, which engages at the corners with the drum and holds the spring in place. A cover or housing, 15, surrounds the drum and parts mounted on the latter; the housing being conveniently held in place by means of a 80 85 bolt, 16, passing through the hub, 13, and the housing.

While the cable may be wrapped around the drum in either direction, I prefer to lead it from its point of attachment to the ring 90 entirely around the ring before it crosses the gap between the two ends. However, no matter in what direction the cable is wound, a pull on the free end thereof tends to tighten it upon the drum, and therefore tends 95 to squeeze or compress the ring tightly about the drum. At the same time, if the pull on the cable is sufficient to overcome the tension of the spring, the ring will be caused to slip or slide around the drum, thus adding its 100 frictional resistance to the resistance of the spring to retard the movement of the cable and ring.

The parts are so proportioned that when 105 the device is placed between two relatively movable members, such as the frame and axle of an automobile, the spring in the device will cause the cable to be wrapped around the drum without leaving any slack when the said members are nearest each other. Consequently, as said members move 110 away from each other, the cable will be un-

wound, pulling the brake ring around upon the drum and thus retarding the separating movement between said members. When said members again approach each other the spring will take up the slack in the cable and move the brake ring in frictional contact with the drum.

It will be seen that the whole inner surface of the ring is at all times in contact with the drum, so that there is no variation in the effective area of the frictional or braking surface of the movable element of the device, as would be the case if the movable brake element were a strap or band wound directly upon the drum so as to be capable of slipping thereon. Uniform pressure on the ring may be maintained at all times by making enough turns of the cable around the drum so that it will at all times be wrapped around the drum at least one whole turn.

I claim:

1. In combination, a circular member, a split element surrounding the periphery of the circular member, resilient means connected to one end of the split element, and a flexible element attached to the said end of the split element completely wrapped around the periphery of the split element and then crossing the gap between the ends of the said element.

2. In combination, a drum, a split brake band surrounding the periphery of the drum and provided with a frictional material on its inner periphery, a spring connected to one end of the split band, and a flexible pulling element attached to the said end of the

split band completely encircling the periphery of the split band and then crossing the gap between the ends thereof.

3. In combination, a stationary drum, a split brake band surrounding the periphery of the drum and provided with a frictional material on its inner periphery, a spring connected at its outer end to the drum and at its inner end to one end of the split band, and a flexible pulling element attached to the said end of the split band completely encircling the periphery of the split band and then crossing the gap between the ends of the said band.

4. In combination, a stationary drum, a clamping plate integral with the said drum, a split element surrounding the periphery of the drum, resilient means connected to one end of the split element, and a flexible pulling element attached to the said end of the split element completely wrapped around the periphery of the split element and then crossing the gap between the ends of the said element.

5. In combination, a stationary drum, a clamping plate integral therewith, a split brake band surrounding the periphery of the drum and provided with a frictional material on its inner periphery, a spring connected at its outer end to the drum and its inner end to one end of the split band, and a flexible pulling element attached to the said end of the split band completely encircling the periphery of the split band and then crossing the gap between the ends of the said band.

SAMUEL FURMIDGE.
